JONATHAN C. MELOON, OF PROVIDENCE, RHODE ISLAND, ASSIGNOR TO
GENERAL FIRE EXTINGUISHER COMPANY, OF NEW YORK, N. Y., A COR-
PORATION OF NEW YORK.

DRY-PIPE VALVE.

No. 857,187.

Specification of Letters Patent.

Patented June 18, 1907.

Application filed September 11, 1902. Serial No. 122,983.

To all whom it may concern:

Be it known that I, JONATHAN C. MELOON, of the city and county of Providence and State of Rhode Island, have invented certain new and useful Improvements in Dry-Pipe Valves, (Case A;) and I do hereby declare the following specification, taken in connection with the accompanying drawings, forming a part of the same, to be a full, clear, and exact description thereof.

The invention relates to dry pipe valves for automatic sprinkler systems, in which a water valve is held closed against the water pressure in the supply pipe by means of a lighter pressure of air or other fluid in the distributing pipes.

The object of the present invention is to provide means for withdrawing the valve from the water way, and so that when the valve is opened there will be a free and unobstructed passage for the water through the valve casing.

To that end the invention consists primarily in the combination, with the valve, of means for withdrawing said valve out of the water way when the apparatus is to operate. The means for thus withdrawing the valve may be either hydraulic or mechanical.

The invention further consists of the combinations and arrangements of parts herein-after described and claimed.

Referring to the drawings, Figure 1 is a vertical section of a dry pipe valve embodying my invention, Fig. 2 is a similar vertical section showing a modified form of valve, Fig. 3 is a similar vertical section showing the same form of valve as in Fig. 2, but with a different means for withdrawing the valve, Fig. 4 is a vertical section on the line Y Y of Figs. 2 and 3, and Fig. 5 is a horizontal section on the line X X of Fig. 3.

Referring to Fig. 1, A represents the valve casing adapted to be connected at its lower end a with the water supply pipe and at its upper end a' with the delivery pipe leading to the sprinkler system. B is a double-seated valve, shown in this figure as a spherical valve, adapted to seat on one side against the fixed valve seat b, and on the other side against the valve seat c formed on the movable member C. As shown in Fig. 1, the movable member C is connected to the valve casing by a flexible connection c', and so that

said movable member may move from the position shown in full lines to the position indicated by dotted lines in Fig. 1. The space between the fixed valve seat b and the movable member C constitutes the intermediate chamber, which is normally open to the atmosphere through a drip pipe d in the usual manner.

The valve casing A is provided with an extension forming a cylindrical chamber E, the outer end of which is closed by a head or cap E'. In this chamber there is a piston F. This piston is connected to the valve B by a suitable connecting link f, pivoted to said piston and to said valve. A small orifice or outlet e is formed in the head E' to permit the escape of air from the chamber E as the piston F travels back therein.

The operation of the apparatus above described is as follows: The air pressure in the distributing pipes acting upon the movable member C forces the valve seat c against the valve B, said valve being in turn forced against the fixed seat b, thereby excluding the entrance of water from the supply pipe. The parts remain in this position until a sprinkler opens and allows the air pressure in the distributing pipes to become reduced below the point at which it will hold the water valve closed. When this happens the water pressure will serve to lift the valve B and with it the movable member C, and the water, flowing into the intermediate chamber E, will act upon the piston F and force it from the position shown in full lines to the position indicated in dotted lines in Fig. 1, thereby pulling the valve B to one side into a space in the valve casing formed to receive it, and thus withdrawing the valve wholly from the water way and leaving a free and unobstructed passage for the water through the valve casing. The piston F is preferably provided with a cup-packing f' which will make a tight joint with the wall of the chamber E, and prevent the escape of water through the orifice e, when the valve B is opened.

Fig. 2 shows a similar construction and arrangement of parts, except that the valve B is here shown as a flat valve, and the movable member C is connected to the valve casing in a slightly different manner. With the spherical valve shown in Fig. 1, it is neces-

sary to provide for a considerable movement of the movable member. With the flat valve shown in Fig. 2 a materially less movement of the movable member is required, and consequently instead of employing an elongated flexible connection, such as shown in Fig. 1, the movable member is shown in Fig. 2 as connected with the valve casing by a connection c^2 which need be simply of a yielding character. Thus said connection c^2 may be formed of thin metal, such as brass, having its inner edge secured to the movable member and its outer edge clamped between the parts of the valve casing.

15 With the flat valve shown in Figs. 2, 3 and 4, means may be conveniently provided for limiting the upward movement of the valve in opening, and for guiding the valve as it is drawn out of the water way. Such means are shown in Fig. 4, and consist of projections a^2 a^2 formed on the inside of the valve casing, said projections being adapted to enter recesses b^2 b^2 formed on opposite edges of the valve B, as shown in Figs. 4 and 5. As will be readily understood from the drawings, the projections a^2 a^2 will serve to limit the extent to which the valve will move upward with the movable member in opening, and will also serve to guide the valve as it is withdrawn from the water way. By extending the projections into the cylindrical casing E, as shown in Fig. 5, said projections will also serve to support the valve in its withdrawn position, and prevent it from falling down into the bottom of the casing. In all other respects the operation of the construction shown in Fig. 2 is the same as that of the construction shown in Fig. 1.

In Fig. 3 mechanical means, in the form of a spring G, is employed, instead of hydraulic means, for pulling the valve B out of the water way. Otherwise the construction is the same as in Fig. 2. As will be understood, when the air pressure is on the system the flat valve B will be firmly clamped and held between the two valve seats b c . Consequently the spring G may be held under tension at this time. When the air pressure is reduced so that the valve B ceases to be firmly clamped, the spring G will act to pull said valve out of the water way.

The valve casing is provided with a suitable hand hole A', through which access may be had to the valve for the purpose of reseating the same. Where a spring is employed to withdraw the valve, the valve may be provided with an eye b^3 , adapted to be engaged by a hook or other suitable instrument, and by means of which the valve may be drawn back to its seat, and held there against the pull of the spring until the valve has been firmly clamped between the two valve seats.

In addition to providing a free and unobstructed passage for the water through the valve casing, the withdrawal of the valve

from its position in the water way also furnishes an effective means for preventing columning of the valve. With the valve thus withdrawn from position, it cannot of course become accidentally reseated or columned.

While it is preferred to have the valve entirely leave the water-way, it is not necessary that this should be done, as with a sufficient movement of the movable valve seat the valve may move only partially out of the water-way and still provide sufficient area for the passage of the water, and it is evident that so far as the feature of non-columning is concerned, a partial withdrawal of the valve will effectively prevent its being reseated or columned.

What I claim as my invention and desire to secure by Letters Patent is:

1. In a dry pipe valve, the combination, with the water-valve, of means for holding said valve closed by pressure in the system, and mechanism arranged to withdraw said valve from the water-way when said valve is released, substantially as described.

2. In a dry pipe valve, the combination, with the water-valve, of means for holding said valve closed by pressure in the system, and mechanism actuated by water pressure arranged to withdraw said valve from the water-way when said valve is released, substantially as described.

3. In a dry pipe valve, the combination, with the water-valve, of means for holding said valve closed by pressure in the system, and mechanism actuated by water pressure from the supply pipe when said valve is released, arranged to withdraw said valve from the water-way, substantially as described.

4. In a dry pipe valve, the combination, with a double seated valve, of a fixed seat for said valve, a movable seat for said valve, said movable seat being mounted upon a movable part adapted to be acted upon by the pressure in the system, and means for withdrawing said valve from the water-way when the pressure in the system is reduced to release said valve, substantially as described.

5. In a dry pipe valve, the combination, with the water-valve, of means for holding said valve closed by pressure in the system, means for limiting the upward movement of said valve when the valve is released, and means for withdrawing said valve from the water-way, substantially as described.

6. In a dry pipe valve, the combination, with the water-valve, of means for holding said valve closed by pressure in the system, mechanism arranged to withdraw said valve from the water-way when said valve is released, and means for guiding said valve in its movement, substantially as described.

7. In a dry pipe valve, the combination of a valve, a fixed seat for said valve and a movable seat for said valve between which fixed and movable seats the valve is clamped as

long as the requisite pressure is maintained in the system, said valve being released and free to leave the water-way when the pressure in the system is reduced, substantially 5 as described.

8. In a dry pipe valve, the combination, with the valve casing, of a valve, a fixed seat for said valve and a movable seat for said valve, between which fixed and movable seats the valve is clamped as long as the requisite pressure in the system is maintained, said valve being released and free to leave the water-way when the pressure in the system is reduced, and said valve casing being provided with a chamber to receive said valve, substantially as described.

9. In a dry pipe valve, the combination of a valve, a fixed seat for said valve, a movable member subjected to the pressure in the system, a valve seat carried by said movable member, between which fixed and movable seats the valve is clamped as long as the requisite pressure is maintained in the system, said valve being released and free to leave the water-way when the pressure in the system is reduced, substantially as described.

10. In a dry pipe valve, the combination of a valve, a fixed seat for said valve, a movable member subjected to the pressure in the system, a valve seat carried by said movable member, between which fixed and movable seats the valve is clamped as long as the requisite pressure is maintained in the system, said valve being released and free to leave the water-way when the pressure in the system is reduced, and means for arresting the movement of the valve in opening before the movable member has reached the limit of its movement, substantially as described.

11. In a dry pipe valve, the combination of a valve, a fixed seat for said valve, a movable seat for said valve, between which seats the valve is normally clamped, said valve being free to leave the water-way when released, and means to guide said valve in its movement out of the water-way, substantially as described.

12. In a dry pipe valve, the combination of a valve, a fixed seat for said valve, a movable seat for said valve, between which seats the valve is normally clamped, said valve being free to leave the water-way when released, means to limit the movement of said valve in opening, and means to guide said valve in its movement out of the water-way, substantially as described.

13. In a dry pipe valve, the combination, with the water valve, of means for holding said valve closed by pressure in the system, and means made operative by the opening of said valve for moving said valve out of working relation with its seat, substantially as described.

14. The combination with a valve, of means for holding said valve closed against pressure by the action of a less pressure, and means other than the valve operated by fluid pressure upon the reduction of the holding pressure for withdrawing said valve to one side of the valve seat.

15. The combination with a valve, of means for holding said valve closed against pressure by the action of a less pressure, a movable member subjected to fluid pressure when the valve opens for withdrawing said valve to one side of the valve seat.

16. The combination with a valve, of means for holding said valve closed against pressure by the action of a less pressure, a piston subjected to fluid pressure when the valve opens for withdrawing said valve to one side of the valve seat.

17. The combination of a chamber, opposing inlet and outlet valve seats, a valve between said valve seats, means for holding the valve and valve seats in engagement against pressure in the inlet by the action of a less pressure, and a movable member subjected to the pressure in the chamber for withdrawing said valve from between said valve seats.

18. The combination of a chamber, a supply inlet, a movable member separating the chamber from the system, an outlet through said member, a valve closing said inlet and outlet and held to its seat by the pressure on the movable member, and means for withdrawing said valve from between the inlet and outlet upon a reduction of pressure in the system.

19. The combination of a chamber, a supply inlet, a movable member separating the chamber from the system, an outlet through said member, a valve closing said inlet and outlet and held to its seat by the pressure on the movable member, a piston subjected to the pressure in the chamber for withdrawing the valve from between the inlet and outlet.
